(57) **CLAIM**

Applicant claims the ornamental design of a chair, as shown and described.

DESCRIPTION

FIG. 1 is a perspective view of a chair embodying the concepts of the present design invention; FIG. 2 is a right side elevational view of the chair of FIG. 1;

FIG. 3 is a left side elevational view of the chair of FIG. 1; FIG. 4 is a front elevational view of the chair of FIG. 1; FIG. 5 is a top plan view of the chair of FIG. 1; and, FIG. 6 is a bottom plan view of the chair of FIG. 1. The broken lines in the above views are for environmental purposes only and form no part of the claimed design invention.
